UNITED STATES PATENT OFFICE.

WILLIAM B. HILGER, OF RIVERTON, IOWA.

CYLINDER FOR GASOLINE ENGINES.

Application filed March 31, 1924. Serial No. 703,014.

This invention relates to improvements in cylinders for gasoline engines and the primary object is to provide sleeves to slidingly operate within the walls of the cylinders relative to the position of the pistons and actuated by means of cams mounted upon the cam shaft located at the side of the cylinders. Another object is to provide sleeves of such design and construction as to permit mounting the spark plugs in their heads. A still further object is to fire the compressed gasoline after the piston rods have passed the dead center upon the down stroke, so as to save the power which is exerted upon the piston while the piston is passing over dead center and to minimize the friction created by the explosion upon the piston during the vertical position of the piston rod and thus give the greatest amount of power obtainable from the least amount of combustible material. These and other objects will be apparent from the accompanying drawings and specification.

In the drawing

Figure 1 is side elevation of an engine equipped with this improvement showing the cam shaft, spring set valve stems and the spring set sleeve actuating rods;

Figure 2 is a longitudinal vertical section through the water jacket and staggered valves, a section being broken away to show the intake and exhaust ports of the sleeves;

Figure 3 is a vertical section of cylinder No. 1;

Figure 4 is a vertical section of cylinder No. 3;

Figure 5 is a vertical section of cylinder No. 4.

Fig. 6 is a vertical section of cylinder No. 2;

Figure 7 is a detail of a sleeve.

Figure 8 is a detail of a sleeve actuating mechanism;

Figure 9 is a detail of a cam that operates the sleeve actuating mechanism;

Figure 10 is a detail of the staggered intake and exhaust valves;

Figures 11, 12, 13, 14, 15 and 16 are diagrammatic views showing the relative position of the sleeves and sleeve operating mechanisms with the pistons and the crank shaft.

In carrying out this improvement upon a gasoline engine, I provide sleeves 1 having intake and exhaust ports 2 and ears 3. The sleeves 1 are adapted to engage the walls of the cylinders 4. Threaded holes 5 are pro-

vided in the heads 6 of the sleeves 1 to permit the mounting of spark plugs 7. Pistons 8 slidingly engage the inner periphery of the sleeves 1. Staggered intake valve 9 and exhaust valves 10 are located in the upper portion at the side of the cylinder block 11 and communicate with the inside of the sleeves 1 through valve chambers 12 and the intake and exhaust ports 13. A cam shaft 13 having valve stem cams 14 rigidly secured thereto, is journaled at the side of the cylinder block 11 below the staggered intake valves 9 and exhaust valves 10. Spring set valve stems 16 engage the valve stem cams 14 to operate the staggered intake valves 9 and exhaust valves 10. Cams 15 are rigidly secured to the cam shaft 13. Rises 24 are incorporated in the cams 15 and so designed to time the vertical motion of the sleeves 1 in relation to the revolutions of the crank shaft 25. Brackets 17 are incorporated in the upper portion of the cylinder block 11 on the side of the staggered intake and exhaust valves 9 and 10. Adjustable spring set rods 18 having eyelets 19 incorporated in their upper portions and rollers 20 mounted in their lower portions engage the cams 15 of the cam shaft 13. Primary links 21 engage the eyelets 19 of the adjustable spring set rods 18 and the ears 3 of the sleeves 1. Secondary links 22 engage the primary links 21 and the brackets 17 of the cylinder block 11. An insulated copper rod 23 is mounted upon the top of the cylinder block 11 opposite the staggered intake and exhaust valves 9 and 10 for providing the spark plugs 7 with electricity for ignition purposes.

In operation, the sleeves 1 are actuated by the cams 15 through the medium of the adjustable spring set rods 18 and the primary links 21. The relative positions of the sleeves 1 with the pistons 8 are as follows: Upon the intake of gasoline into the sleeves 1, the said sleeves 1 are at the top of the cylinders 4 and remain there until the pistons 8 have reached the top of the compression stroke, whereupon the sleeves 1 begin to move downward with the pistons 8 at a slightly faster rate and gain a trifle on the pistons 8, thereby increasing the compression of the compressed gasoline until the spark plugs 7 mounted in the heads 6 of the sleeves 1 come in contact with the insulated copper rod 23 to ignite the compressed gasoline. At the beginning of the

exhaust stroke the sleeves 1 raise a trifle, thereby completely opening the valve chambers 12 of the valves 10 to permit the exhaust gases to escape, and remain in that 5 position until the pistons 8 are within approximately one-half of an inch of the sleeve heads, so as to force practically all of the exhaust gases out of the sleeves whereupon the said sleeves 1 raise to the top of the 10 cylinders 4 to permit the intake of gasoline through the valves 9 upon the downward stroke of the said pistons 8 as illustrated in Figures 11, 12, 13, 14, 15 and 16.

While I have herein described a certain 15 specific method of constructing and assembling the elements of my invention, it is understood same may be varied in minor details, not departing from the spirit of my invention as defined in the appended claims.

20 I claim:

1. In a device of the kind described embodying in conjunction with the cylinder block of a combustion engine, sleeves engaging the inner periphery of the cylinders 25 of said block, said sleeves being provided with peripheral apertures near their heads adapted to communicate with staggered intake and exhaust valve chambers; and a cam shaft and cam means for reciprocating 30 said sleeves.

2. In a device of the kind described, a

sleeve formed with a head engaging the inner periphery of the cylinders of an internal combustion engine, said sleeve being provided with peripheral apertures for communicating with the intake and exhaust chambers of said engine; and a cam shaft and cam means operated by said engine for depressing said sleeve at the time of compression for holding compression to enable 40 delaying the firing of the compressed combustible material until the crankshaft has passed dead center.

3. In a device of the kind described, a movable cylinder sleeve formed with a head 45 adapted for internal engagement by the piston, said sleeve being formed with lateral peripheral apertures adapted to communicate with staggered intake and exhaust valves; a cam shaft and cam means for depressing said sleeve upon the compression stroke of the piston and holding said compression to facilitate retarding the igniting of the compressed combustible materials until the crankshaft has passed dead center, 50 and then raising said sleeve in the proper time for communication with the staggered valves thru the peripheral apertures of said sleeve.

In testimony whereof I affix my signature.

WILLIAM B. HILGER.
